UNITED STATES PATENT OFFICE.

FREDRICK C. MILLER, OF NEWPORT, KENTUCKY.

DESIGN FOR A COUPLING-REACH FOR ROLLER-SKATES.

SPECIFICATION forming part of Design No. 16,128, dated June 16, 1885.

Application filed April 25, 1885. Term of patent 14 years.

To all whom it may concern:

Be it known that I, FREDRICK C. MILLER, a citizen of the United States, residing at Newport, in the county of Campbell and State of Kentucky, have invented and produced a new and original Design for a Coupling-Reach for Roller-Skates, of which the following is a specification, reference being had to the accompanying drawings, forming part thereof.

10 Figure I is a side elevation, and Fig. II a plan, of my novel design. Fig. III is a transverse section of the reach on the line III III, Figs. I and II.

The novel feature of the present design for coupling-reaches for roller-skates consists in the particular shape or configuration of the sides and top of such coupling-reaches, the reach having an arched or curved bar with longitudinal ribs or beads 2 at the top and bottom, concentric with each other, cross-bars 5, panel 1, inclosed by the ribs or beads and the cross-bars, openings 6 between the ends of the ribs or beads, standards 3, surmounting the

ends of the ribs or beads 2, flattened tops 4 to the standards, holes 4^a, and pins or posts 7 and 25 8 on the bar and one of the tops. The bar as thus shaped is of I form in cross-section at its panel portion, with rounded upper and lower surfaces, 9 and 10.

Having thus described my design, the following is what I claim as new therein and desire to secure by Letters Patent:

The design for a coupling-reach for roller-skates herein shown and described, the same consisting of an arched or curved bar having 35 ribs or beads at the top and bottom, concentric with each other, openings in the ends, cross-bars near the ends, standards over the ends, a flat top surmounting one standard, and an inclined top surmounting the other stand- 40 ard.

FREDRICK C. MILLER.
